UNITED STATES PATENT OFFICE.

JACOB ULLRICH, OF HOBOKEN, NEW JERSEY.

STYLOGRAPHIC PEN.

No. 878,914.

Specification of Letters Patent.

Patented Feb. 11, 1908.

Application filed October 15, 1907. Serial No. 397,581.

To all whom it may concern:

Be it known that I, JACOB ULLRICH, a citizen of the United States, residing at Hoboken, Hudson county, State of New Jersey, 5 have invented new and useful Improvements in Stylographic Pens, of which the following is a specification.

This invention relates to an improved stylographic pen and more particularly to an 10 improved construction of the connecting means between the needle and the air tube of such pen.

In the accompanying drawing: Figure 1 is a longitudinal section of my improved 15 stylographic pen; Fig. 2 an enlarged longitudinal section through the lower end thereof, and Fig. 3 a cross section on line 3-3, Fig. 2.

The tubular barrel 10 of the pen inclosing 20 the ink reservoir 11 is threaded at its lower end as at 12 for engagement with the nozzle 13. Within barrel 10 is inclosed an air tube 14 communicating with the atmosphere through vent 15 of barrel 10. The outer 25 diameter of tube 14 is less than the inner diameter of nozzle 13, so that a clearance is formed around the tube, through which the ink may flow from reservoir 11 into nozzle 13.

The air from tube 14 enters the ink reservoir 30 10 or nozzle 13 through a lateral outlet 16 of the tube.

The bore of air tube 14 is enlarged at its bottom to form an integral housing inclosing a chamber 17 for the reception of a 35 head 18 formed on the heel of needle 19.

Within the lower end of chamber 17 is fitted a perforated bushing 20 which encompasses needle 19 and serves to confine head 18 within chamber 17. A spiral spring 21 interposed between head 18 and a shoulder 22 40 formed on upper end of chamber 17 within housing tends to push needle 19 outward through nozzle 13.

In connecting the parts, spring 21 and headed end of needle 19 are introduced from 45 below into chamber 17, and then bushing 20 is slipped over the needle and permanently fitted into the lower end of tube 14. In this way the construction of the parts is simplified, and they may be readily assembled with 50 a minimum expenditure of time and labor.

I claim:

A stylographic pen provided with an ink barrel, an inclosed air tube having an expanded lower bore to form an integral housing and a shoulder at the upper end of said housing, a nozzle communicating with the ink barrel, a perforated bushing in the bottom of the housing, a needle passing through the bushing and having a head within the housing, and a spring within the housing that engages said shoulder and head, substantially as specified. 55 60

Signed by me at New York city, (Manhattan,) N. Y., this 14th day of October, 65 1907.

JACOB ULLRICH.
